UNITED STATES PATENT OFFICE.

ARTHUR M. SCHOFIELD, OF AMHERST, OHIO.

APPARATUS FOR HYDRATING LIME.

1,204,700.

Specification of Letters Patent. Patented Nov. 14, 1916.

Original application filed January 31, 1916, Serial No. 75,382. Divided and this application filed June 12, 1916. Serial No. 103,181.

To all whom it may concern:

Be it known that I, ARTHUR M. SCHOFIELD, a citizen of the United States, residing at Amherst, in the county of Lorain and State 5 of Ohio, have invented a new and useful Apparatus for Hydrating Lime, of which the following is a specification.

The device forming the subject matter of this application discloses matter divided out 10 of my prior application for a process and apparatus for hydrating lime, Serial No. 75,382, filed on the 31st day of January, 1916.

One object of the present invention is to 15 provide a novel means whereby steam is generated when water is admitted onto the lime and, more specifically, whereby the heat produced may be concentrated and retained at the point where heat is necessary, 20 in order to bring about the best possible results when the water is admitted onto the lime.

A further object of the invention is to 25 provide novel means whereby the heat thus generated may be made effective for any desired purpose.

Another object of the invention is to provide novel means whereby the heat generated in the manner hereinbefore stated may 30 be used for heating the water which is admitted onto the lime.

In addition to the foregoing, the invention contemplates novel means whereby the container may be sealed to prevent the 35 escape of steam, thereby to render the heat generated efficient for the ends above stated, it being possible to admit the lime into the container, and to permit the slaked lime to pass therefrom, without producing any appreciable diminution of the steam pressure within the container.

The invention aims to provide novel means for feeding the unslaked lime into the container.

It is within the province of the disclosure 45 to improve generally and to enhance the utility of devices of that type herein disclosed.

With the above and other objects in view 50 which will appear as the description proceeds, the invention resides in the combination and arrangement of parts and in the details of construction hereinafter described and claimed, it being understood that 55 changes in the precise embodiment of the

invention herein disclosed can be made within the scope of what is claimed, without departing from the spirit of the invention.

In the accompanying drawings:—Figure 1 60 shows in side elevation, a lime hydrating apparatus embodying the present invention, parts being broken away; Fig. 2 is a top plan of the structure shown in Fig. 1; Fig. 3 is a sectional diagrammatic representation 65 of the apparatus; Fig. 4 is a cross section taken adjacent the forward end of the container, the parts appearing for the most part in elevation; Fig. 5 is a fragmental longitudinal section taken along the line 70 5—5 of Fig. 4; Fig. 6 is a section taken approximately along the line 6—6 of Fig. 1; Fig. 7 is a fragmental top plan showing a portion of the means whereby a feeding of the unslaked lime is brought about; Fig. 8 75 is a side elevation of the structure shown in Fig. 7; and Fig. 9 is a fragmental vertical section showing one of the discharge nozzles whereby water is introduced onto the unslaked lime within the container. 80

In carrying out the present invention there is provided a tubular container denoted generally by the numeral 1 and embodying an outer shell 2 and an inner shell 3. The container 1 includes a rear head 4 and a front head 5. The container 1 may be upheld in a substantially horizontal position in any desired manner, as by supports 6.

At its forward end, the container 1 is provided with an inlet 7 for unslaked lime. In the inlet 7 is journaled a shaft 8 including a plurality of blades 9. The sides of the inlet 7 are curved as shown at 10, so as to co-operate with the edges of the blades 9, the construction being such that, although the blades 9 will advance unslaked lime into the container 1, any appreciable leakage of steam from the interior of the container 1 through the inlet 7 will be prevented. The inlet 7 ordinarily communicates with a chute 11 adapted to receive the contents of a bin 12 wherein unslaked lime is stored. 90 95 100

The container 1 is provided, near to its rear end, with a depending outlet 14 in which is journaled for rotation a shaft 15 carrying blades 16 adapted to co-operate with the curved sides 17 of outlet, as described in connection with the blades 9 and inlet 7. The construction is such that, 105 110

although the slaked lime may pass through outlet 14, any appreciable leakage of steam generated within the container 1 will be avoided.

5 Extended longitudinally of the container 1 is a main shaft 18, the same being journaled in the heads 4 and 5 and, if desired, being journaled on bearings 19 located within the container. Secured to the main 10 shaft 18 and located within the container 1 are a plurality of sets of blades, three sets being shown in the present instance. Referring to the diagrammatic figure which is numbered 3, the blades of the first set are 15 denoted by the numeral 20, the blades of the second set are denoted by the numerals 21 and 22, and the blades of the third set are denoted by the numerals 23 and 24. The blades 20 of the first set, that is, the set 20 adjacent the forward end of the machine, are all so pitched as to advance the lime when the shaft 18 is rotated. The blades 21 of the second set are so pitched as to advance the lime, the blades 22 being so 25 pitched as to retard the lime. In the third set, that is, the set which is adjacent the rear end of the machine, the blades 23 are advancing blades, the blades 24 being retarding blades. The number in each set and 30 the relative arrangement of the blades therein may be altered, depending upon the character of the lime which is being handled. Preferably, however, the blades 20 of the first set are all advancing blades. In 35 the intermediate set, one third of the blades are adapted to advance the material, and two thirds are adapted to retard it. In the last set, that is, the set adjacent the rear end of the machine, one quarter of the blades are 40 pitched to advance the material, and three quarters are pitched to retard the material. These proportions will be varied in practice, but represent a fair average.

The shaft 15 which operates the means for 45 sealing the outlet 14 may be connected operatively with the main shaft 18 in any desired manner. In the present embodiment of the invention, a sprocket wheel 25 is secured to the exposed rear end of the shaft 18, a sprocket wheel 26 is secured to the 50 shaft 15, and about the sprocket wheels is trained a sprocket chain 65.

Any suitable means may be provided for 55 driving the shaft 18. If desired, this driving means may include a shaft 27, journaled in bearings 28 and provided with a pinion 29 meshing into a gear wheel 30 carried by a shaft 31 journaled in bearings 32. A pinion 33 on the shaft 31 meshes into a gear 60 wheel 34 carried by the main shaft 18, the main shaft being journaled at its end in a bearing 35 exterior to the container 1.

A means is employed whereby a step-by-step rotation is imparted to shaft 8, to feed 65 the unslaked lime into the container 1.

With this end in view, the shaft 31 is provided as shown in Fig. 4 with a crank disk 36 carrying a wrist pin 37 coacting with a socket 38 into which is connected one end of a connecting rod 39, the other end of the connecting rod being threaded into a socket 40. A lock nut 41 is threaded onto the rod 39 and coacts with the socket 40. As shown most clearly in Figs. 7 and 8, a frame 42 is mounted to swing on the shaft 8 of the lime feeding mechanism, a ratchet wheel 43 being secured to the shaft 8, within the contour of the frame. Mounted to rock in one end of the frame 42 is a shaft 44 carrying a pawl 45 adapted to coact with the ratchet wheel 43. Assembled with the end of the shaft 44 is a weight 46 which serves to maintain pawl 45 in engagement with the ratchet wheel 43. A cross member 47 is mounted to move longitudinally of the frame 42, in slots 48 formed in the sides of the frame and shown best in Fig. 8. The position of the cross member may be adjusted, longitudinally of the frame, by means of a screw 49 cooperating with the cross member and the frame. 90 The socket 40 which is carried by the upper end of the connecting rod 39 is mounted to swing on the cross member 47. The lime-feeding mechanism above described may be changed without jeopardizing the utility of 95 the invention. It is necessary merely that there shall be a continuous flow of unslaked lime in proper proportion to the amount of water delivered, and that the egress of steam be prevented. 100

Intermediate the ends of the container 1, the walls 2 and 3 thereof are separated by a partition or wall 50, providing adjacent the rear end of the container a water space 52, and defining adjacent the forward end of the container a heat-insulating space 53 which may contain a heat resisting material 51. At a point spaced from the rear end of the container 1, opposed portions of the water space 52 are connected by circulating tubes 54, lying within the container 1 as best shown in Fig. 6. A water inlet 55 for the space 52 is provided, and the water outlet may be in the form of a pipe 56. The pipe 56 may lead to any point 110 where hot water or steam is desired, but in the present instance, the pipe 56 leads to a water storage tank 57, disposed on top of the lime bin 12 or elsewhere. The tank 57 is provided with an overflow outlet 58 and leading from the tank is a discharge conduit 59 carrying a regulating and indicating valve 60 of any desired sort. The stem of the valve 60 may carry a finger 60^a adapted to coöperate with a scale 60^b. The lower end of the conduit 59 communicates with a cross pipe 61 disposed adjacent the head 5 of the container as shown most clearly in Fig. 4. Projecting from the cross pipe 61 are nipples 62 coöperating with noz- 115 120 125 130

zles 63 (Fig. 9) mounted in the head 5, each nozzle being equipped with an outlet 64.

The operation of feeding unslaked lime from the bin 12 into the container 1 is as follows. When the shaft 31 is rotated, the crank disk 36 and the wrist pin 37 impart a reciprocating movement to the connecting rod 39, the latter tilting the frame 42, whereupon pawl 45 will acutate the ratchet wheel 43 and the shaft 8, the blades 9 swinging in close relation to the curved side walls 10 of the inlet 7, and admitting the lime in greater or less quantities. In this connection it should be noted that the blades 9 seal the inlet 7 practically steam-tight, so that steam generated within the container 1 as hereinafter described may not escape. An adjustment is provided whereby the angular position of the arc of the throw of the frame 42 may be regulated. This adjustment is brought about by rotating the connecting rod 39 which is threaded into the sockets 38 and 40, the effective length of the connecting rod thus being changed. This adjustment ordinarily is made by the erector and represents an average adjustment. A further adjustment to regulate the throw of the frame 42 may be brought about by rotating the screw 49, thus to cause the cross member 47 to move toward and away from the axis of the shaft 8, thereby varying the effective length of the frame 42. The adjustment last above described preferably is made by the operator in control of the machine. Owing to the construction above pointed out, the amount of lime fed into the container 1 may be regulated.

The driving train for the shaft 18 embodies the pinion 29, the gear wheel 30, the shaft 31, pinion 33 and the gear wheel 34.

As hereinbefore mentioned, the shaft 15 which operates in the outlet 14 is driven from the shaft 18 by the sprocket wheel 25, the sprocket chain 65 and the sprocket wheel 26.

Water is delivered onto the unslaked lime at the forward end of the container 1 by the pipe 59 and the nozzles 63. As the lime is thus slaking, steam and heat are generated. In this connection it is to be observed that, adjacent its forward end, the container 1 is surrounded by the heat resisting material 51, so as to retain the heat. The heat, therefore, is held at a point whereby heat is most necessary, in order to facilitate the chemical reaction between the water and the unslaked lime.

As the lime moves along the container 1, through the instrumentality of a means, the operation of which will be explained hereinafter, the lime ultimately arrives in the zone surrounded by the water jacket 52. The heat in the lime thus is abstracted, so that the lime leaves the machine at a point approximating as closely as possible, the

temperature of the surrounding atmosphere. The heat thus abstracted warms the water in jacket 52 to a point adjacent or above boiling. When it is recalled that every pound of lime which is slaked has given off 500 British thermal units, or approximately one-horse power, it will be obvious that if the present machine has but a low efficiency, a considerable amount of energy may be saved, to be utilized for any purpose. If desired, water heated in the manner hereinbefore described, may be delivered into the tank 57 and may pass by way of the pipe 59, onto the unslaked lime.

As to the manner in which the blades 20, 21, 22, and 23 operate on the lime, it will be recalled that the blades 20 are all adapted to advance the lime at the forward end of the container 1 and while the lime is in a granular and plastic form, the lime when 85 in this condition requiring the most potent means for advancing it. Owing to the relation existing between the blades 21 and 22 of the intermediate set, the blades 21 being advancing blades and the blades 22 being 90 retracting or retarding blades, the lime is held as long as necessary in this zone, the general tendency of the lime being to advance, owing to its finely divided condition. When the lime reaches that set of blades 95 which is located adjacent the rear end of the container, the lime is retarded to a maximum extent, in order that it may remain as long as necessary within the zone defined by the water jacket 52, so that the heat may 100 be absorbed from the lime and that the lime may leave the container 1 in a comparatively cool condition.

By a proper manipulation of the valve 60 and by effecting a proper throw of the frame 42, the amount of water and the amount of lime delivered to the container 1 may be regulated, it being customary in practice to combine the lime and the water in proportion to their chemical equivalents. 110

The operation of the structure forming the subject matter of this application is practically continuous, and the container is sealed so that the steam may be maintained therein. The device herein disclosed is so constructed that the heat produced as the lime is slaking may be saved and may be applied to any useful purpose, such as heating the water which is delivered onto the unslaked lime.

The container 1 may be provided with all of the usual adjuncts, such as man holes 75, a sampler 76 and the like.

Having thus described the invention, what is claimed as new is:

1. A lime hydrator embodying a container; means for admitting lime to the container; a lime outlet for the container; means for admitting water to the container; a heat retaining jacket located on the con- 130

tainer adjacent the means for admitting lime; a water jacket located on the container adjacent the outlet; an inlet for the jacket; and an outlet for the jacket.

- 5 2. In a lime hydrator, a container; a lime inlet for the container; a lime outlet for the container; means for admitting water to the container; means for retaining adjacent the inlet, the heat created by the slaking of the lime; and means for salvaging, adjacent the

outlet, the heat created by the slaking of the lime.

In testimony that I claim the foregoing as my own, I have hereto affixed my signature in the presence of two witnesses.

ARTHUR M. SCHOFIELD.
